(57) **CLAIM**

The ornamental design for a tub spout, as shown and described.

DESCRIPTION

FIG. 1 is a front perspective view of a tub spout showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the photographic area define the bounds of the claimed design and form no part thereof. The unshaded areas within the broken lines form no part of the claimed design.

1 Claim, 7 Drawing Sheets
